UNITED STATES PATENT OFFICE.

CHARLES H. BUCKNAM, OF PORTLAND, MAINE.

RECLINING-CHAIR.

SPECIFICATION forming part of Letters Patent No. 250,879, dated December 13, 1881.

Application filed March 24, 1881. (No model.)

To all whom it may concern:

Be it known that I, CHARLES H. BUCKNAM, residing in Portland, in the county of Cumberland and State of Maine, have invented certain new and useful Improvements in Reclining-Chairs; and I do hereby declare that the following is a full, clear, and exact description of the invention, which will enable others skilled in the art to which it appertains to make and use the same.

This invention relates especially to a new and ingenious improvement in that class of chairs commonly known and designated as "adjustable reclining-chairs;" and the object thereof is to furnish a reclining-chair which shall be so constructed and have its several operating parts so arranged that the back of the chair can be easily adjusted to stand firmly set at an oblique angle, varying more or less from the nearly perpendicular position common to the backs of all chairs, to suit the taste and convenience of the person using the chair; also, a chair that shall have among its several working parts simple and effectively-operating mechanical devices for returning the back of the chair to its normal upright position, when desired, with practically little or no muscular effort.

To successfully accomplish this object the invention consists in fastening to the under side of the arm-rests closed guides or slideways and attaching to said slideways a spring clutch or clamp; also, in using jointed and notched catch-rods, which extend from the frame-work of the back of the chair forward through slots cut in the tops of the rear supports of the arm-rests, thence under the arm-rests and through the slideways, the clamps attached to said slideways fitting into and engaging with the notches cut in the catch-rods; also, as will hereinafter be shown, in skillfully attaching to the rear rail of the seat-frame and connecting the same to the frame of the chair-back a spring of any convenient description, which shall act by its recoiling power to carry the back of the chair to an upright position when it is not desirable to use the chair for reclining purposes.

In order that the nature of the said invention may be fully understood, reference is hereby made to the subjoined specification, in which it is explicitly set out, and to the annexed drawings illustrating it, in which—

Figure 1 is a front elevation of a chair-frame. Fig. 2 is a top plan of the same, partly in section. Fig. 3 shows a sectional view through the line of intersection xx . Figs. 4 and 5 are details of the closed slideways and catch-rods. Fig. 6 is an enlarged detail of the clutch used in clamping the catch-rods. Fig. 7 is a detail of the spring used in operating the chair-back. 60

Similar letters of reference indicate corresponding parts.

The construction is as follows:

A A are the rear legs of a reclining-chair frame; B B, the front legs. These legs are joined and firmly held together by the rear and front seat-rails, C C, and the side seat-rails, D D. The back of the chair, which is denoted by E, is hinged to the tops of the rear legs, A A, at the point a .

F F represent arm-rests, which are stationary. To the under side of the arm-rests guides or slideways bb are fastened in any convenient manner. These guides or slideways are made up of two side sections, as shown in Figs. 4 and 5. Each side section has a lip, as shown at $b'b'$ in the bottom-plan view, Fig. 3, extending part way along one edge, and when the two sections are fitted together the lip of one side section overlaps and matches with the lip of the other section. This method of overlapping forms a closed slideway for a catch-rod to run in, and at the same time operates to lock the sections firmly together. One of the sections is provided with an elevation, d , which serves as a bearing for the spindle of a spring clutch or clamp, G. This spring-clutch is made up of a spindle, g , which is surrounded by a spiral spring. One end of the spindle is provided with a knob or handle, g' . The other is fitted into an angular-shaped piece, g'' . When the clutches G are in their proper positions the knobs project outward beyond the sides of the chair, and the angles g'' fit into slots m cut in the insides of the slideways. The spiral springs on the spindles, being compressed between the knobs and the slideways, tend by their recoil to hold the angles g'' firmly thrust into the slots.

H H show catch-rods, made in two sections. The rear sections, ff , are attached to lugs hh , fastened to the frame of the chair-back. From the back the sections ff extend toward the front of the chair, passing through slots

cut in the tops of arm-rest supports *n n*, and at the points *z z* are joined to the other sections, *o o*, which pass between and through the slideways *b b*. The sections *o o* are made with 5 a series of notches or slots, *p p*, which are to receive the angles *g²*.

Rigidly attached to C—the rear rail of the seat-frame—are two blocks, *i i*. One end of each of the blocks is turned round, and around 10 the turned parts coils K K, of stout spring-wire, are wound. The coils are firmly fastened to or about the blocks, so that there shall be no slipping or turning when the spring is subjected to a severe strain. An end of the spring 15 passes from the coil to any convenient point on the frame of the chair-back, and is there fastened.

Having thus described the manner of constructing my said invention, I will now explain 20 its operation.

When the back of the chair is in its usual upright position, as shown in Fig. 1, and the user is desirous of changing it to an oblique angle, easy for lounging or reclining purposes, 25 by pressing on the knobs *g'* the angles *g²* will be pushed back out of the slots *m m* and disengaged from the notches *p p* of the catch-rods *o o*. The catch-rods will then be free to move longitudinally through the slideways. By holding 30 the catch firmly in the position just indicated and putting pressure upon the chair-back, the back will turn on the hinges *a a* and be carried backward and downward, drawing the catch-rods through the slideways. As soon 35 as the desired angle is obtained, by relaxing the pressure on the knobs *g'* the compressed coil-spring on the catch-spindle will elongate, and the angle *g²* will be thrust through the slots *m m*, where it will engage with the notches 40 of the catch-rod. Thus the chair-back will be held firmly and securely at a reclining angle. To return the chair-back to its upright position, pressing upon the knobs will thrust the 45 angles out of the notches and slots, as before, and the recoiling force of the springs K K will

send the back to its normal upright position. The free end of the spring K is caught to the back of the chair by a hook, *h*. This manner of fastening it is of great service in attaching and detaching when making or repairing the 50 chair.

In returning the back from an oblique reclining angle to an upright position it is not necessary to exert pressure upon the back to relieve the catches from any strain caused by 55 the springs K K.

In some devices of this kind the pressure on the locking clutch or clamp is so strong that it cannot be operated easily; but in my invention the clutch is so constructed that the angle *g²* can be pressed out of the notches and slideways, no matter how much strain may be exerted by the springs K K. 60

What I claim as my invention, and desire to secure by Letters Patent, is— 65

1. The slideways *b b*, fixed beneath the stationary arm-rests F, made in two sections, and otherwise constructed substantially in the form and manner herein shown and described, and the clutches or clamps G G, in combination 70 with each other and with the notched catch-rods H H, substantially as and for the purposes herein set forth.

2. The spiral spring K, attached to the rear rail, *i*, of the chair-seat, and having an upwardly-extending end playing in the lug *h* on the chair-back, substantially as described. 75

3. The combination of spring K, attached to the rear chair-rail, *i*, and having an upwardly-extending end, with the chair-back E, provided 80 with a guide-lug, *h*, and with the notched catch-rod H, guides or slideway b, stationary arm F, and spring-clutch G, substantially as described.

In testimony that I claim the foregoing as my own I have affixed my signature in presence of two witnesses. 85

CHARLES H. BUCKNAM.
